UNITED STATES PATENT OFFICE.

ROBERT BINGHAM WASSON, OF CRANFORD, NEW JERSEY.

RING-TENSIONING MACHINE.

Application filed January 8, 1923. Serial No. 611,273.

My invention relates to a machine for condensing metallic packing or piston rings, said machine including a condensing roller for creating permanent stress in the ring blank.

One of the objects of my invention is to provide a machine which varies the magnitude of these stresses in accordance with a predetermined law so that when piston or packing rings, i. e., expanding or contracting rings, are condensed in the machine, they will exert substantial uniform radial pressure per unit of area of contact when confined in the engine cylinder or bearing in which they are utilized. The law which gives the pressure applied to the pressure applying roller is the law of the crank with a long connecting rod, so as to vary the magnitude of the stresses given the ring.

20 The principles governing a ring which tends to contract with substantially uniform pressure from its expanded condition or to expand with substantially uniform pressure from its contracted condition through its own inherent stresses are the same. The invention can be applied to one as readily as to the other by reversing the positions of the condensing tool and ring supporting member with relation to the ring. For the sake of 25 clearness these drawings and specifications describe the mechanism covering the expanding type of ring only but it is to be understood that the invention is not limited to the manufacture of rings of this type.

30 Another object of the invention is to provide such a machine which controls and varies the stresses in a piston ring in such a manner that they are unbalanced according to a predetermined law and so that they cause 35 the ring to twist about a circumferential axis and translate this twist into a substantially uniform pressure per unit of area of contact localized toward one edge of the ring when the ring is confined in the engine cylinder. The twist is in accordance with a predetermined law, the twist, when the ring is 40 in a free state, being least at the split and most at the point opposite the split and varies between these two points in accordance with 45 the law, the twist increasing first gradually then more rapidly, then less rapidly and reaching its maximum 180° away from the 50

zero point. The zero point is at the middle of the split portion.

Other objects of the invention are to provide a condensing roller of tapered or frustoconical shape which will condense one of the curved faces of the ring so as to cause the ring to twist; to locate and vary the position of the condensing roller with reference to the line of pressure, depending on the size of the ring to be condensed; to apply the pressure by a crank mechanism or equivalent mechanism so that the pressure will be applied by the correct predetermined law, to provide for changing the fulcrum of one of the links through which the pressure is applied thereby enabling the pressure to be varied when working on rings of different radial thickness; to provide for two or more springs of different strength for transmitting the pressure—a light spring for applying the pressure at the points at the split portions of light rings and a heavy spring for pressure beyond the points of light or heavy rings.

With the above and other objects in view, my invention consists in the parts, improvements and combinations more fully pointed out hereinafter.

Referring now to the drawings:

Fig. 1 is a plan view looking down on the top of the machine.

Fig. 2 is a plan view on a larger scale showing the right hand end of the machine, illustrating details of the driving mechanism of the ring holder and of the means for rotating it.

Fig. 3, is an end elevation looking toward the end of the machine at the right of Fig. 1.

Fig. 4 is a section, full size, passing through the ring holder on the line 4—4 of Fig. 1.

Fig. 5, is a section, full size taken through the ring holder at right angles to the section taken on line 4—4; Fig. 5 being taken on the line 5—5 of Fig. 1.

Figs. 6 and 7 are sectional details illustrating the operation of condensing the ring, the parts being illustrated in two positions. These sections are taken on the line 6—6 of Fig. 2.

Fig. 8 is a sectional plan view showing the support for the roller which condenses the ring, as well as the ring while being condensed. This section is taken on line 8—8 of

Fig. 4. In Fig. 8 the dot and dash circle illustrates on an exaggerated scale the circumference of the opening 27 of the ring holder.

Fig. 9 is an elevation illustrating a portion 5 of the unclutching mechanism of the machine.

Fig. 10 is a sectional detail on line 10—10 of Fig. 8.

Fig. 11 is a plan view illustrating the mechanism for moving the pressure applying roller omitting some of the associated parts.

Fig. 12, is a sectional detail on line 12—12 of Fig. 1, showing part of the stop mechanism.

15 Fig. 13, is a longitudinal sectional view on line 13—13 of Fig. 1, passing through the pressure applying roller and the springs associated therewith, and also illustrating part of the fulcrum shifting mechanism.

20 Fig. 14, is a transverse section on line 14—14 of Fig. 1.

Fig. 15, is a transverse sectional view on line 15—15 of Fig. 1, illustrating the adjustable crank and one of the cams of the fulcrum 25 shifting mechanism.

Fig. 16, is a longitudinal sectional view taken on line 16—16 of Fig. 1, illustrating the adjustable crank and one of the cams of the fulcrum shifting mechanism.

30 Figs. 17 and 18 are two sectional views on line 17—17 of Fig. 1, illustrating the unloading mechanism for moving the chuck, permitting the removal of the ring, the parts being shown in two positions in the two figures.

35 Fig. 19, is a view of the mechanism for controlling the shift of the fulcrum of the pressure applying roller mechanism and also illustrates the unclutching mechanism of the machine.

40 Referring again to the drawings, the reference numeral 1 denotes the bed of the machine which is pivoted at trunnions 2, 3 and 4 to upward extension 5 of the base 6. The bedplate 1, may have one or more downwardly pivoting arms 7, which are provided with 45 bolts 8 to engage arcuate slots 9 in the parts 5 of the base 6 (Fig. 3). The pivots being coaxial with the main driving shaft, this enables the bed of the machine to be swung at 50 any angle and secured there so the operator may work on the machine in a horizontal plane as shown in the drawings or it may be tilted to any desired angle, so as to permit ready inspection and adjustment of the working parts mounted on the bedplate.

55 Means are provided for driving the machine, as follows:

60 Mounted in bearings 10 and 11 is the main driving shaft 12, which has secured to it, the worm 13, that engages the worm wheels 14 and 15. A gear 16 is secured to said shaft 12 and is in mesh with a pinion 17 on a counter shaft 18, which may be driven in any suitable manner. The worm wheel 14 rotates 65 the piston ring carrying mechanism and the

worm wheel 15, operates the pressure applying mechanism when condensing the ring.

The rotation of the shaft 12 is controlled by the clutch 19 which is shifted to the clutching or unclutching position by the lever 20, pivoted at 21 in lugs on the bed 1. The clutch may be thrown into or out of engagement by the handle 22 or automatically by suitable mechanism hereafter described.

The means for holding the ring while it is 75 being subjected to the condensing forces which give the ring radial pressure and twist will now be described.

80 A rotary member such as a worm wheel 14 has secured to it the carrier 23 by bolts 24, located near the outer periphery of the worm wheel 14. The carrier 23 is rabbeted or shouldered at 25 for engagement with the ring holder 26. The holder is locked to the carrier by a pin 25^a. This holder as shown in the drawings is removable and the opening 27 may be of any desired size to accommodate various sizes of rings and may be a suitable shoe for large rings. The piston ring "a" to be condensed and twisted is of a 85 slightly less diameter than the diameter of the opening 27 of the holder. The outer edge or periphery of the member 23 is engaged by the pressure applying roller 28, which tends to yieldingly force the worm wheel 14 and the carrier 23 and holder 26, carrying the ring "a", against the condensing roller 29. The mechanism for holding the condensing roller 29 and for providing the yielding 90 pressure for the pressure applying roller 28, 100 while the ring is being condensed so as to give it radial pressure and a twist will be hereafter described.

95 In the machine illustrated the piston ring may be condensed after or before it has been 105 split. The piston ring being of a slightly less diameter than the diameter of the opening 27 of the ring holder as illustrated more particularly in Fig. 8, a very advantageous 110 result is obtained.

115 As the holder and ring are rotated and the small condensing roller 29 and the top and bottom rollers are held in place, that is to say, being allowed no bodily movement but merely revolve, the ring and its containing 120 holder in effect are drawn through and pass between the bite of the bottom and top rollers and the condensing roller. The yielding pressure is maintained by the pressure applying mechanism, the effect being that the circumferential increase in the ring is not retarded and the radial pressure remains undisturbed while the width of the ring is not 125 permitted to increase, the radial thickness diminishing slightly under pressure. Means 130 are thus provided for gripping the ring blank while being condensed and also permitting the entire blank to increase its circumferential dimension so that the flow of metal circumferentially in the ring is not retarded. 135

The worm wheel 14 is made in the form of a ring and a circular plate 30, with the shoulder 31 fits in the opening. This plate 30 is secured to the bedplate 1 by bolts 32, which 5 pass through openings 33 in said bedplate and prevent upward displacement of the plate 30 but allow a horizontal movement. The bolts have shoulders 34 which prevent binding of the plate 30 when the threaded 10 end is tightened up. The shoulder 31, on the plate 30, holds the worm wheel 14 in place and a construction is thus provided whereby the worm wheel 14 and its associated parts are suitably supported for rotating and 15 yet may move in the direction on which the force is applied.

The plate 30 has a cut out part 35 in which is located the block 36 which supports the condensing roller 29. This block 36 engages 20 the sides of the cut out portion 35 of the plate 30 and allows the plate and its associated parts to move only in the direction in which the pressure is applied and prevents movement of the plate transverse to the line of 25 pressure. The bed plate 1 is also provided with a shouldered slot 37 in which the block 36 is held stationary and is adjusted by the adjusting bolt 38 which is threaded at its outer end in the bedplate 1 and has the groove 30 39 on its inner end, said groove being engaged by the pin 40 secured in the block 36. The only time it is necessary to change the position of the block is when the diameter of the ring to be condensed is changed. A 35 tongue 41 sliding in slot 42 and attached by screw 42^a to the block 36 supports the ring at a point opposite the condensing roller.

Secured to the block 36 is the stud 43 upon which is mounted the roller bearing 44, which 40 supports the condensing roller 29. This roller is of a comparatively small diameter. The greatest practical difference in magnitude of the area of contact between roller and ring and holder and ring is desirable. It is known from experience in peening or hammering rings, that once established, any variation in the relation of these areas, one to 45 the other, such as the wear of the striking point etc., results in a variable product which will not meet the requirements. My condensing roller and the ring holder overcome these difficulties. The roller is preferably of less diameter and of less length than the axial width of the ring. 50 The roller in the best embodiment of the invention is slightly tapered or frusto conical, as shown in the drawings (see Figs. 5, 6, and 7). By making use of a tapered roller, as illustrated or by utilizing a cylindrical roller located to one side of the central plane of the ring, this will compress one edge of the ring more than the other and throw the forces produced in the metal out of balance, in accordance with a predetermined law which produces a very desirable effect in the finished 55

ring, namely a twist in the ring which increases the pressure at the contacting edge of the ring when it is in the cylinder. The roller is positioned slightly off the center line as shown in Fig. 8, and is freely movable or floating. It is located off the line of pressure and at the near side of the line which a point of the ring approaches before it is condensed. This enables a heavy pressure to be applied to the roller and ring. Means are provided for supporting the roller against pressure. In the form shown the roller is supported on the annular ring 45, which in turn is carried by the rollers 46 of the bearing 44.

Means are provided for securing a very 60 fine adjustment of the position of the roller 29. A housing 47 is provided, said housing having a pair of lugs 48 each having an adjusting screw 49 which contacts with opposite sides of a stud 50 carried by the block 36. 65 The roller is located in a cut out notch 51 of the housing and a glass hardened pin 52 is located on the side of the notch (see Figs. 8 and 10) toward which the roller is forced, when the ring is being tensioned. The roller moves 70 slightly in the notch 51 toward the pin. Some play is provided in notch 51 for the purpose (see Fig. 10). Its bodily movement then stops. It rotates as the ring holder and ring 75 continues to turn. The pin 52 may be turned 80 to present another surface and is readily renewed if at any time it becomes somewhat worn. The roller 29 has axial extensions 29^a, which keep the roller substantially upright 85 by contact with the top and bottom portions 90 of housing 47 at the notch.

A plate 53 secured to the bed 1 by the bolts 54 supports the block 36 and, the shoulders 37 prevent any upward displacement of said block. The plate 53 is suitably grooved and slotted at 53^a to allow the parts secured to the block to be moved when adjustment is being made. Means are provided for relieving the pressure on the roller 29 so that the rings may be readily placed into or removed from the 95 chuck, which means will be hereafter described.

Means are provided for confining the condensations in metal to a radial and circumferential direction and so as to prevent a lateral flow of metal across the width of the ring. Under the law of pressure applied to the ring by the condensing roller the condensing effect at the points of the ring or at zero degree, is very small, but increases variably to 115 180°. Very near the zero degree the force applied must be sufficient to cause the metal to flow and permanently condense through the annual section of the ring. In accordance 120 with the invention this flow is limited to a circumferential flow and any substantial change in the width of the face of the blank is prevented which would require correcting operations and introduce further variables.

A roller 55 is held to the block by plates 55^a. 130

This roller supports the under face of the ring "a" to be condensed and thus also helps to eliminate friction. As stated above, means are provided for condensing the inside of the ring in such a way as to give it a twist.

A roller 56 (see Figs. 4, 5, and 7) is positioned so as to be brought in contact with the upper face of the ring when it is being condensed. It is thus seen that the inner face of the ring is supported by the roller 55, the outer face by the holder 26 and the upper face confined by the roller 56. Preferably, the top and bottom rollers overlap the flat faces of the ring and the condensing roller is shorter than the axial width of the ring. Thus when the ring is revolved, when it is condensed by the condensing roller 29, the metal is confined and the condensations are confined to a radial and circumferential direction. Moreover, the upper and lower rollers being driven by frictional contact with the ring holder 26 help to turn the ring "a" (see Fig. 7). The lines of pressure between the top and bottom roller and the rings should be substantially in the same plane with the line of pressure between the condensing roller and the ring so as to prevent unequal condensations of the metal of the top and bottom faces of the ring. Means for adjusting the top and bottom rollers are provided.

When the roller 29 is adjusted as above described the top (56) and the bottom (55) rollers are also adjusted, the bottom roller being adjusted by means of shims (not shown).

The roller 56 is pivoted on a stud 57 which is mounted in a block 58 having a slotted connection 59 with the arm 60, the slotted connection permitting accurate positioning of said roller 56. The arm 60 is pivoted on a short shaft 61, which is located above the main driving shaft. By raising or lowering the arm 60, the roller 56 is moved in or out of contact with the piston ring "a".

The free end of the arm 60 has suitable means for holding it down in the position shown particularly in Figs. 1, 2, 3 and 4. A plate 62 has a pair of lugs 63 integral with it, between which the free end of arm 60 drops when said arm is swung down. An adjustable stop bolt 64 threaded into the plate 62 between the lugs acts as a stop to prevent the arm 60 from being forced down too hard and creating too much pressure on the piston ring to be rolled. The lower part of said plate 62 has a shoulder 65 to cooperate with a slot 66 in the bed plate 1. The plate also has a clearance hole 67 for the bolt 68 which is threaded for a substantial part of its length.

When the plate 62 is properly located it is held rigidly in position. The bolt 68 is threaded into the nut 69 at its lower end and a nut 70 is provided at the intermediate part of said bolt above the plate. The nut 70 is

shown provided with a handle 71 so as to facilitate loosening said nut when it is desired to move the plate, after which movement the nut may be turned so as to lock the bolt and plates in position.

On the upper part of said bolt 68 is mounted a cam 72 provided with a handle for holding the arm 60 in position. As shown in Fig. 2, one side of this cam member 72 is slabbed off as at 73 so that when it is turned counterclockwise from the position shown in Fig. 2, it will be clear of the end of the arm 60 and said arm may be readily raised. A pin 74 working in the annular groove 75, in the bolt 68 (see Fig. 4) allows the cam handle to be rotated without it being moved up or down.

When it is desired to change the size of the ring that the machine is condensing, the arm 60 is repositioned on the shaft 61, the nut 70 is loosened and the bolt 68 carrying the mechanism for holding down the arm 60 is correspondingly relocated, thus relocating and securing the roller 56 in place.

The pressure applying means for forcing the pressure applying roller 28 against the holder 26 will now be described. The roller 28 is pivoted on a stud 76 mounted in the slide block 77 which slides in guides 78 in the bed plate 1. Plates 79 confine the block 77 in position in the guides. Means are provided for transmitting a yielding, spring pressure to the block and for adjusting the springs. The block has mounted in the side opposite the roller 28 a stud 80 which has threaded on it two nuts 81 and 82. A flange 83 butts up against the block 77 and has a series of holes in which a suitable tool may be used to rotate the stud 80 and thus move the nuts 81 and 82.

A heavy spring 84 is confined between the larger nut 81 and the wall 85 of a head 86. A lighter spring 87 is confined between the smaller nut 82 and the wall of the head 86. One or all of the springs are so set as to exert an initial pressure on the roller 28 which through the mechanism heretofore described forces the piston ring "a" against the condensing roller 29. Under certain conditions it is desirable to vary the initial pressure and this is done by regulating the positions of the nuts 81 and 82 thus giving the springs 84 and 87, more or less power. The amount of free coils of the springs and the length of the springs under compression is thus varied. In addition the compression of the springs is varied. In the drawings two springs are shown. To take care of different sizes of rings and to compensate for irregularities in the structure of the iron more springs may be provided. These springs may be so arranged that the heavier ones will not come into play until the ring has been revolved a part of a turn. This arrangement is particularly valuable because

the grey iron of which it is preferable to make the ring has substantial variations in its properties that may be compensated for.

In the drawings in Figure 13, both springs 5 are shown in contact at their ends, they thus act, so to speak, as one spring. The machine may be arranged so that the light spring is initially in contact at its ends with the slide block nut and head, and the heavy spring is 10 supported by nut 81 but is not initially in contact with the head 86, but comes into contact after the light spring has been compressed (see Fig. 11). One or both nuts as will be seen may be threaded into the springs so as 15 to vary the number of effective coils of the spring leaving a greater or less number of free coils.

There are a number of methods of adjusting the springs, one being by the rotation of 20 flange collar 83 and screw bolt, the second by the rotation of collar 81 and the spring simultaneously, the third by the rotation of collar 82 and the small spring simultaneously, the fourth being by the rotation of collar 81 into 25 the large spring 84 and a fifth being the rotation of collar 82 into the small spring thus altering its free length. In other words, both springs may be susceptible to adjustment for initial pressure as well as adjustment for free 30 length which covers all pressures between the initial pressure and the terminal pressure.

It is desirable when tensioning the ring with one revolution of the holder to start with an initial pressure and under a predetermined law to increase the pressure until the pressure has been applied half way around the ring, at which point maximum pressure is being applied. Then the pressure is decreased under the same predetermined law 40 until we come back to our starting point, having made one complete revolution of the ring, and again have our initial pressure. The law which gives the pressure applied to the pressure applying roller is the law of the 45 crank with a long connecting rod; this pressure is in turn transferred to the metal of the ring, the amount and variation of the resulting compression of the metal of the ring depending on the particular kind of metal or 50 cast iron of which the ring is composed. By adjusting the parts of the pressure applying mechanism, the amount of pressure can be regulated and the ring condensed so as to give equal radial outward pressure. The result 55 may be checked by the ring testing gage. On smaller sized rings one revolution is all that has been found necessary and the pressure applying mechanism will first be described for condensing the ring in one revolution.

60 On large size rings it is desirable to revolve the ring a number of times depending upon conditions. Moreover, metals require time in which to flow. If the time element is too short to permit the full amount of flow 65 in the metal the result will vary as the metal

is harder or softer. To meet some requirements, it is necessary to subject the inner surface of large rings to the condensing pressure two or more times. Means are provided for doing this and for building up a greater 70 pressure for each successive revolution. This will be described hereafter.

The means for varying the pressure under a predetermined law when the ring is being tensioned with one revolution will now be 75 described. The head 86 is mounted to slide in the aforesaid mentioned guides 78, and has pivoted on the stud 88 the link 89 which is fulcrumed on the block 90 in the slot 91 of the link 89. Pivoted to the opposite end of the 80 link 89 is the connecting rod 92. The other end of the connecting rod 92 has a slot 93 in which is located the block 94. The block 94 has the bushing 95 therein, which acts as a bearing and has secured in it the stud 96. 85

Means are provided for adjusting the throw of the stud 96 which stud serves as a crank pin. The lower end of the stud 96 is made in the form of a slide 97 and has threaded therein an adjusting bolt 98 which is secured against longitudinal movement by the pins 99 mounted in the disc 100 and working in the annular groove 101 of the threaded part of the adjusting bolt which may revolve in the hole 102 of the disc 100 (see Fig. 16). A 90 nut 103 on the upper end of the stud 96 is tightened when the block 94 is properly positioned by the adjusting screw 98. This nut holds the block rigidly to the bushing 95 but the bushing is free to rotate in the block. The 95 disc 100 has guiding grooves 104 for the slide 97 on the lower end of the stud 96 and said disc is rigidly held to the worm wheel 15 by bolts 105.

Means are provided for locking this block 100 in its adjusted position. One edge of the block 94 is serrated and engages corresponding serrations 106 on one edge of an angle shaped plate 107. This angle shaped plate 107 is bolted at 108, to the connecting 110 rod 92. It will be noted that the block 94 is adjusted eccentrically or off center in relation to the center of the worm wheel 15 and it is plain from the foregoing description that as the worm wheel 15 is revolved by the worm 115 13, the connecting rod 92 will be given a certain predetermined throw which will be transferred to the link 89 and will apply the pressure to the ring through the mechanism heretofore described. By loosening 120 the block 94 and relocking it the connecting rod 92 and link 89 may be adjusted to reposition the link when the crank throw is changed so as to preserve the right-angled relation between the connecting rod and link. 125 Means are provided for varying the maximum pressure applied when condensing rings of different thickness.

The fulcrum block 90 of the link 89 is mounted on a member 109 which is engaged 130

by an adjusting and holding screw 110 (see Fig. 14). This adjusting screw is mounted in the bed plate 1 so as to be free to be rotated and has the handle 111 at its outer end and is threaded at 112 to engage the member 109.

Thus by turning the adjusting screw the position of the fulcrum block 90 may be changed and more or less pressure applied to the ring according to the position of said block 90. Fig. 11 shows a plan view of the mechanism employed in condensing the ring when one revolution is adequate to give the desired results.

When the ring has been given one complete revolution suitable mechanism is provided to stop the machine and this will now be described. Secured to the lower part of the head 86 and passing through a slot 113 in the bed plate 1, is a pin 114 which at the proper time engages a lever 115 pivoted on the bed plate at 116. The opposite end of the lever 115 from that engaged by the pin 114 is bifurcated and a rod 117 passes through the bifurcated part. This rod is mounted in extensions in the bed plate 1 and carries a collar 118 which is engaged at the proper time by the bifurcated part of the lever 115. The outer end of this rod is in contact with one leg of an angle shaped member 119 which is pivoted at 120 in a lug on the bed plate. The other leg of the member 119 has a shoulder 121 that holds the clutch lever 20. A pin 122 mounted in the bed plate has a spring 123, that forces said pin against the lever 20. Another collar 124 is mounted on the shaft 117 and a spring 125 between this collar and one of the depending lugs from the bed plate keeps the collar 118 in contact with the bifurcated part of the lever 115.

From the foregoing it will be understood that as the pin 114 is moved away from the work after the revolution has been completed and the ring condensed, it engages the lever 115 and the opposite end of said lever engages the collar 118 which being fast on the rod 117 causes the rod to move and the outer end of the rod operating on the member 119 releases the lever 20. The lever 20 is forced outward by the pin 122 and the spring 123 and disengages the clutch 16 which stops the machine. The machine may be stopped before an entire revolution of the ring is completed, the stop motion being so set. Symmetrical portions of the ring on each side of the middle may thus be rolled without rolling the portions of the split.

The ring holder being larger in diameter than the ring blank, the ring blank will have passed over the condensing roller before the ring holder has completed its cycle of 360°. By adjusting the stop motion mechanism so as to stop the machine when the last end of the ring has been rolled and putting the ring in the holder so as to begin condensing near the initial zero position of the ring, this dif-

ference is compensated for. Means are provided so that the stop motion may be adjusted and instead of stopping the machine and completing the cycle of pressure applied to the ring on a complete revolution of the ring holder, its cycle can begin at the zero position for one point of the ring and will end after the ring has been rolled and the other point of the ring has been reached. This occurs before the holder which is larger than the ring has made a complete revolution. The ring creeps in the holder due to its increase in circumferential length and the mechanism compensates for this creeping. This mechanism is illustrated particularly in Figs. 14, 15, 16 and 19.

As previously explained in revolving and condensing the ring a number of times, on each successive revolution an increasing pressure between the points is applied, the initial pressure applied at the points remaining substantially constant. This is accomplished by shifting the fulcrum 90 in the link 89 and thus giving the head 86 more movement on each successive rotation of the ring and compressing the springs 84 and 87, thereby applying more pressure each time.

The worm wheel 15 is secured or made integral with the shaft 126 which has a bearing in the bushing 127 mounted in the bed plate 1. The lower end of the shaft is turned down slightly and has secured to it the drum cam 128 by means of the nuts 129. Pivoted at 130 in lugs on the bed plate 1 is the slotted lever 131, which has mounted near its upper end the cam roller 132 for engagement with the cam groove 133 in the drum cam 128.

Connections are provided for shifting the fulcrum at each successive revolution of the ring. The cams and levers are so proportioned and arranged with reference to the fulcrum and with reference to the position of the ring in its holder that the shifting of the fulcrum takes place at each revolution, within a few degrees from the split portion of the ring, namely a few degrees at each side of the zero degree point of the ring.

The opposite end of the connecting rod 135 is pivoted in an ear on a rack bar 136. At its intermediate part the connecting rod 135 has a turn buckle 137 by which the rod may be lengthened or shortened when being adjusted in different positions in the slot 132, so as to make it possible to vary the amount of movement of the rack bar.

The rack bar 136 is mounted, so that it may be reciprocated in the lower part of a yoke 138 secured to the bed plate 1. The lower part of this yoke is grooved and the rack is held in position by plates 139 suitably secured to the yoke. The teeth of the rack engage a pinion 140 that is keyed to a sleeve 141, the pinion being positioned between the two arms of the yoke 138.

The sleeve 141 has pinned to it at 142, one

arm of a pawl carrying frame 143. Adjacent to this and pinned at 144 to the shaft 145 is the ratchet wheel 146. The shaft 145 has bearings in the yoke 138 and lug 147, dependent from the bedplate 1. The frame 143, for the other arm of which the shaft provided a bearing, carries the pawl 148 which is held in engagement with the teeth of the ratchet wheel 146 by a spring 149.

10 By the above mechanism the rotation of the stud 126, reciprocates rack 136 and through pinion 140 turns pawl carrier 143 so that pawl 148 will turn the shaft 145 part of a revolution.

15 The shaft 145 has secured to it the drum cam 150, the cam groove 151 of which is engaged by a projection 152 from the block 109 that carries the fulcrum 90. When the machine is operated by the mechanism just described the adjusting screw 110 is disconnected entirely from the block 109.

From the foregoing it may be understood that the amount of movement that will be given the rack 136 and transferred by the ratchet 146 and pinion 140 to the shaft 145 will be governed by the position of the connecting rod 135 in the slot of the lever 131. The ratchet wheel 146 as illustrated in the drawing has twenty four teeth and the parts 20 may be so adjusted that on each movement of the pawl one tooth, or any number corresponding to a factor of 24 may be taken. Thus the parts may be adjusted so as to reciprocate the rack 24, 12, 8, 6, 4, 3 or 2 times in order to give one revolution to shaft 145. This means that the ring will be condensed that number of times while the shaft 145 and the cam 150 are making one complete revolution. The cam groove in the cam 150 is so 25 laid out that its shifts the fulcrum at each revolution and accomplishes the desired effect on the rings. The cam groove may be made adjustable so that it may be readily changed when it is desired to give the ring a different number of revolutions or a plurality of cams may be provided and the proper one selected for the number of revolution to be given the ring. Moreover the cam groove is arranged so as to bring the fulcrum back to 30 its initial position after the ring has been rolled the required number of times.

When the machine is being operated as previously described to condense the ring with only one revolution the connecting rod 135 is disconnected and the parts just described do not function. The position of the block 109 is then maintained fixed by the adjusting screw 110.

35 The means for stopping the machine after the ring has been condensed the required number of times, where a plurality of rotations of the ring are utilized, include a cam 152 (see Fig. 8) mounted on the end of the shaft 145. The high spot on this cam strikes

the end of the shaft 117 at the completion of a 40 revolution of the shaft 145 and this operates the mechanism heretofore described to stop the machine.

A tool 154 is mounted on a flexible member 155 held in the arm 60 by the bolt 156. By 45 tapping this tool prior to tensioning a ring, the ring may be marked so that it may be split in the proper place, when the ring is condensed before splitting.

Suitable means, previously mentioned, for 50 relieving the pressure on the pressure applying roller, when a ring is to be removed and another one inserted will now be described. This unloading mechanism is shown particularly in Figs. 17 and 18.

55 Secured to the shaft 61 is a cam 157 which is engaged by a member 158 pivoted at 159 to a lug on the bearing 11. This member 158 has two ears 160 and 161 which engage the high and low parts of the cam 157. Pivoted 60 at 162 to the lower part of the member 158 is a link 163 which is slotted or bifurcated at 164 and slightly beveled off at 165 (see Fig. 2). This beveled part engages a small block 166 having a corresponding bevel so that a wedging action is obtained when the parts engage. The block 166 has a pin 167 mounted in a hole 168 in a boss on the bed plate 1.

70 When the parts are in the position shown in Fig. 17, the arm 60 is down and the ring is confined in the holder. The ear 160 is on the high part of the cam and the ear 161 is on the low part and the link 163 has drawn its beveled end 165 out of engagement the block 166 thus allowing the member 23 to be forced over by the springs 84 and 87 against the condensing roller 29. When the arm 60 is raised preparatory to removing a condensed ring and inserting another, the parts assume the position shown in Fig. 18. The ear 160 is then on a low part of cam 157 and the ear 161 on the high part and the beveled face 165 has wedged the block 166 over, which relieves the pressure of the springs and the ring may be removed and another inserted.

75 The operation of the machine will now be briefly described. The condensing of the piston ring with one revolution of the holder will first be considered.

The arm 60 is raised, the clutch lever 20 80 has been thrown out and the clutch 19 is released and the machine stopped. The unloading mechanism has been automatically operated as previously described by raising the arm 60 and pressure has been relieved on condensing roller 29 so that a ring may be readily inserted.

85 The ring is inserted in the holder 26 and the arm 60 lowered thus withdrawing the link 163 of the un-loading mechanism and allowing the springs 84 and 87 to force the roller 28 against the member 23 which allows the initial pressure to be set up against the con-

densing roller 29. The lever 20 is then pushed inward by hand and the shoulder 121 on the member 119 latches over the lever and holds it in place.

5 The clutch 19 being engaged rotates the shaft 12, which through the worm 13 rotates the worm wheels 14 and 15 so that the said wheels rotate in synchronism. As explained the worm wheel 14 carries the piston ring holder and the worm wheel 15 operates the pressure applying mechanism through the connecting rod 92, link 89 and head 86.

10 As the revolution is completed the pin 114 operating on the lever 115 and shaft 117 kicks the member 119 out of engagement with the lever 20 and the pin 122 swings the lever outward and operates the clutch to stop the machine.

15 As previously explained when the machine is being operated this way, the position of the fulcrum 90 in the link 89 is controlled by the screw 110 and the connecting rod 135 is disconnected so that the parts carried on the shaft will not function.

20 When it is desired to operate the machine so as to condense the ring a plurality of times the screw 110 is disconnected from the block 107 and the connecting rod 135 is connected to the slotted lever 131 and the rack 136.

25 Suppose for example it is desired to condense and revolve the ring six times to obtain the desired result. The bolt 134 is positioned in the slot of the lever 131 so that it will move the rack 136 through the medium of the connecting rod 135, a sufficient distance to rotate the pinion 140 so that, in turn, will move the pawl 148 over four teeth of the ratchet wheel 146. Then as the rack is drawn back by the connecting rod under control of the cam 128, the shaft 145 will be given one-sixth of a revolution. The fulcrum will be advanced through the cam 150 on said shaft 145 and the ring will be condensed during one revolution with a certain pressure. This pressure will be increased until the shaft 145 has made a complete revolution and the ring has been condensed six times, and the fulcrum has returned to its initial position.

30 The cam 152 will then operate the mechanism to stop the machine, the arm 60 may be raised, relieving the pressure through the unloading mechanism and the ring removed.

35 Having thus described the invention it will be understood that changes may be made therein without departing from the principle of the invention.

I claim:

40 1. In a machine for condensing piston rings the combination of a holder for the ring, a condensing roller arranged to contact with the inside of the ring, a pressure applying roller arranged to apply pressure to the holder, and means for varying the pressure applied to said pressure applying roller so as to vari-

ably condense different portions of the completed ring. 65

2. In a machine for condensing piston rings the combination of a holder for the ring, a condensing roller arranged to contact with one of the curved faces of the ring, a pressure applying roller, and means for varying the pressure applied to said pressure applying roller so as to variably condense different portions of the completed ring. 70

3. In a machine for condensing piston rings the combination of a holder for the ring, a condensing roller arranged to contact with one of the curved faces of the ring, a pressure applying roller, a crank for varying the pressure applied to said pressure applying roller, 75 80 in accordance with a predetermined law.

4. In a machine for condensing piston rings, the combination of a holder for the ring, a condensing roller arranged to contact with the inside of the ring, a pressure applying roller, a crank for varying the pressure applied to said pressure applying roller in accordance with a predetermined law and means for adjusting the throw of said crank. 85

5. In a machine for condensing piston rings in accordance with a predetermined law, the combination of a holder for the ring, a condensing roller arranged to contact with the inside of the ring, a pressure applying roller, a rotary member, a link mechanism between said member and the pressure applying roller, said link mechanism including a lever, a fulcrum for said lever, the rotation of said rotary member applying pressure to said pressure applying roller through said link mechanism. 90 95 100

6. In a machine for condensing piston rings in accordance with a pre-determined law the combination of a condensing roller arranged to contact with the inside of the ring, a sliding pressure applying roller, a slide block in which the pressure applying roller is mounted, a rotary member, link mechanism between said member and the pressure applying roller, said link mechanism including a lever, a fulcrum for said lever, the rotation of said rotary member applying pressure to said slide block through said link mechanism. 105 110

7. In a machine for condensing piston rings the combination of a holder for the ring, a tapered condensing roller arranged to contact with the inside of the ring, a pressure applying roller arranged to apply pressure to the holder and means for varying the pressure applied to said pressure applying roller so as to variably condense different portions of the completed ring. 115 120

8. In a machine for condensing piston rings the combination of a holder for the ring, a condensing roller arranged to contact with the inside of the ring, means whereby the surface of said roller is presented at an angle to the inner surface of the ring, a pressure ap-

plying roller arranged to apply pressure to the holder and means for varying the pressure applied to said pressure applying roller so as to variably condense different portions of the completed ring.

9. In a machine for condensing piston rings the combination of a holder for the ring, a condensing roller arranged to contact with the inside of the ring, a pressure applying roller arranged to apply pressure to the holder, means for locating said condensing roller at one side of the line of pressure, and means for varying the pressure applied to said pressure applying roller so as to variably condense different portions of the completed ring.

10. In a machine for condensing piston rings the combination of a holder for the ring, means for rotating the holder, a condensing roller arranged to contact with one of the curved faces of the ring, said roller being free to move bodily in the direction of rotation of the ring, a pressure applying roller, arranged to apply pressure to holder and means for varying the pressure applied to said pressure applying roller so as to variably condense different portions of the completed ring.

11. In a machine for condensing piston rings, the combination of a holder for the ring, a condensing roller arranged to contact with the inside of the ring, a housing for said roller, means for adjusting said housing so as to position said roller, a pressure applying roller arranged to apply pressure to the holder and means for varying the pressure applied to said pressure applying roller so as to variably condense different portions of the completed ring.

12. In a machine for condensing piston rings, the combination of a holder for the ring, a condensing roller arranged to contact with the inside of the ring, a housing provided with a notch, said notch freely receiving said roller, a screw for adjusting said housing so as to position said roller, a pressure applying roller arranged to apply pressure to the holder and means for varying the pressure applied to said pressure applying roller so as to variably condense different portions of the completed ring.

13. In a machine for condensing piston rings, the combination of a holder for the ring, a condensing roller arranged to contact with the inside of the ring, a pressure applying roller arranged to apply pressure to the holder and means for varying the pressure applied to said pressure applying roller in accordance with a predetermined law, a rotatable ring for supporting the condensing roller against pressure and a ball bearing for said ring.

14. In a machine for condensing piston rings the combination of a holder for the ring, a condensing roller arranged to contact with

the inside of the ring, a pressure applying roller arranged to apply pressure to the holder, means for varying the pressure applied to said pressure applying roller in accordance with a predetermined law, a rotatable ring for supporting said roller against pressure, a block carrying said ring, and means for adjusting said block relative to the line of pressure thereby providing for condensing rings of different diameters.

15. In a machine for condensing piston rings the combination of a holder for the ring, a gear, means for securing said holder to said gear, means for rotating said gear, a condensing roller arranged to contact with the inside of the ring, a pressure applying roller arranged to apply pressure to the holder and means for varying the pressure applied to said pressure applying roller so as to variably condense different portions of the completed ring.

16. In a machine for condensing piston rings, the combination of a holder for the ring, a gear, means for securing said holder to said gear, a drive shaft, said shaft being geared to said gear, a condensing roller arranged to contact with the inside of the ring, a pressure applying roller arranged to apply pressure to the holder and a second gear driven from said drive shaft, a crank pin carried by said second gear, and connection between said crank pin and the pressure applying roller.

17. In a machine for condensing piston rings the combination of a holder for the ring, a gear, means for securing said holder to said gear, a drive shaft, said drive shaft carrying a worm, said worm driving said gear, a condensing roller arranged to contact with the inside of the ring, a pressure applying roller arranged to apply pressure to the holder and a second gear driven from said worm, a crank pin carried by the face of the second gear and connections including a spring for varying the pressure applied to said pressure applying roller in accordance with a predetermined law.

18. In a machine for condensing piston rings, the combination of a bed plate, a drive shaft extending along said plate, a worm carried by said shaft, a pair of gears meshing with said worm and arranged on opposite sides of said drive shaft, a ring holder secured to the face of one of the said gears, a condensing roller arranged to engage the inside of said ring, said ring holder being bodily movable in the direction of the pressure, a crank pin carried by the other of said gears, a connecting rod having one end connected to said crank pin, a lever to which the other end of the connecting rod is connected, a pressure applying roller, and a yielding connection between said pressure applying roller and said lever.

19. In a machine for condensing piston

rings, the combination of a holder for the ring, a gear, means for securing said holder to said gear, a plate about which said gear rotates, a condensing roller arranged to contact with the inside of the ring, a pressure applying roller arranged to apply pressure to the holder, and means for varying the pressure applied to said pressure applying roller so as to variably condense different portions of the completed ring.

20. In a machine for condensing piston rings, the combination of a holder for the ring, a gear, means for securing said holder to said gear, a plate about which said gear rotates, means for mounting said plate so as to permit movement thereof in the direction in which the force is applied, a condensing roller arranged to contact with the inside of the ring, a pressure applying roller, arranged to apply pressure to the holder, and means for varying the pressure applied to said pressure applying roller so as to variably condense different portions of the completed ring.

25. 21. In a machine for condensing piston rings, the combination of a holder for the ring, a gear, means for securing said holder to said gear, a plate about which said gear rotates, means for mounting said plate so as to permit movement thereof in the direction in which the force is applied, means for preventing movement of said plate transverse to the line of pressure, a condensing roller arranged to contact with the inside of the ring, a pressure applying roller arranged to apply pressure to the holder, and means for varying the pressure applied to said pressure applying roller so as to variably condense different portions of the completed ring.

30. 22. In a machine for condensing piston rings, the combination of a holder for the ring, a gear, means for securing said holder to said gear, a circular plate having a cut-out portion, a block fitting said cut-out portion, so as to permit movement of the plate only in the direction in which the force is applied, a condensing roller arranged to contact with the inside of the ring, a pressure applying roller, arranged to apply pressure to the holder, and means for varying the pressure applied to said pressure applying roller so as to variably condense different portions of the completed ring.

35. 23. In a machine for condensing piston rings, the combination of a holder for the ring, a condensing roller arranged to contact with the inside of the ring, a pressure applying roller arranged to apply pressure to the holder, means for varying the pressure applied to said pressure applying roller in accordance with a predetermined law, and means contacting with and inwardly overlapping the faces of the ring for confining the flow of metal within the ring, while the ring 40 is being condensed by the condensing roller.

24. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, and rollers contacting with the faces of the ring for confining the flow of 45 metal within the ring, while the ring is being condensed by the condensing roller.

25. In a machine for condensing piston rings, the combination of a holder for the ring, a condensing roller arranged to contact with the inside of the ring, a block, a support for supporting the condensing roller against pressure carried by the block contacting with one face of the ring and an upper roller contacting with the other face of the ring whereby the flow of metal is confined within the ring, a pressure applying roller arranged to apply pressure to the holder and means for varying the pressure applied to said pressure applying roller so as to variably condense 50 different portions of the completed ring.

26. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller and means for locking 55 said arm down.

27. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller and a screw and cam for locking 60 said arm down.

28. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller, a stop for the arm and a screw and cam for locking 65 said arm down.

29. In a machine for condensing piston rings, the combination of a holder for ring, a condensing roller arranged to contact with the inside of the ring, a pressure applying roller arranged to apply pressure to the holder, means for varying the pressure applied to said pressure applying roller in accordance with a predetermined law, an upper and lower roller contacting respectively with the upper and lower face of the ring, a shiftable, pivoted arm carrying the upper roller, a screw and cam for locking said arm down, and means for bodily adjusting said screw and cam when the arm is shifted for different sized rings. 70
30. In a machine for condensing piston rings in accordance with a predetermined law, the combination of a holder for the ring, a condensing roller arranged to contact with the inside of the ring, a pressure applying roller, a rotary member, link mechanism between said member and the pressure applying roller, said link mechanism including a lever, a fulcrum for said lever, and means for adjusting said fulcrum, the rotation of said rotary member producing and applying pressure to said pressure applying roller thru said link mechanism. 80
31. In a machine for condensing piston rings in accordance with a predetermined law, the combination of a holder for the ring, a condensing roller arranged to contact with the inside of the ring, a pressure applying roller, a rotary member, link mechanism between said member and the pressure applying roller, said link mechanism including a lever, a fulcrum for said lever, and a screw for adjusting said fulcrum, the rotation of said rotary member producing and applying pressure to said pressure applying roller thru said link mechanism. 90
32. In a machine for condensing piston rings, the combination of a holder for the ring, a condensing roller arranged to contact with the inside of the ring, a pressure applying roller, a crank pin connected to the pressure applying roller for varying the pressure applied to said pressure applying roller in accordance with a predetermined law, a rotary member carrying said crank pin, and means for adjusting the throw of said crank pin. 100
33. In a machine for condensing piston rings, the combination of a holder for the ring, a condensing roller arranged to contact with the inside of the ring, a pressure applying roller, a rotatable gear, an adjusting screw carried by said gear, an adjustable crank pin connected with said screw, a link connected at one end to said crank pin and connections between said link and said pressure applying roller. 110
34. In a machine for condensing piston rings, the combination of a holder for the ring, a condensing roller arranged to contact with the inside of the ring, a pressure applying roller, a rotatable gear, an adjusting screw carried by said gear, an adjustable crank pin connected with said screw, and means for locking said crank pin in its adjusted position. 115
35. In a machine for condensing piston rings, the combination of a holder for the ring, a condensing roller arranged to contact with the inside of the ring, a pressure applying roller, a rotatable gear, an adjusting screw carried by said gear, an adjustable crank pin connected with said screw, a link having a slot at one end, a slide block mounted in said slot, said crank pin being mounted within said slide block. 120
36. In a machine for condensing piston rings, the combination of a holder for the ring, a condensing roller arranged to contact with the inside of the ring, a pressure applying roller, a rotatable gear, an adjusting screw carried by said gear, an adjustable crank pin connected with said screw, a link having a slot at one end, a slide block mounted in said slot, said crank pin being mounted within said slide block, and a locking plate cooperating with said slide block for locking said crank pin in its adjusted position. 125
37. In a machine for condensing piston rings, the combination of a holder for the ring, a condensing roller arranged to contact with the inside of the ring, the diameter of said roller being less than the axial width of the ring, a pressure applying roller arranged to apply pressure to the holder, a plurality of springs for transmitting pressure to said pressure applying roller, and means for varying the pressure applied to said springs in accordance with a predetermined law. 130
38. In a machine for condensing piston rings, the combination of a holder for the ring, a condensing roller arranged to contact with the inside of the ring, the length of the body of said roller being less than the axial width of said ring, a pressure applying roller arranged to apply pressure to the holder, springs between the holder and the pressure applying roller, and means for varying the pressure applied to said springs in accordance with a predetermined law. 135
39. In a machine for condensing piston rings in accordance with a predetermined law, the combination of a rotary holder for the ring, a condensing roller arranged to contact with the inside of the ring, a sliding pressure applying roller, a slide block in which the pressure applying roller is mounted, a rotary member, a movable head, connections between said head and said rotary member, and a spring between said head and said slide block, the rotation of said rotary member moving said head and applying pressure to said slide block thru said spring and connections. 140
40. In a machine for condensing piston

rings in accordance with a predetermined law, the combination of a condensing roller arranged to contact with the inside of the ring, a sliding pressure applying roller, a slide block on which the pressure applying roller is mounted, a rotary member, a movable head, connections between said head and said rotary member and a heavy spring and a light spring between said head and said slide block, the rotation of said rotary member moving said head and applying pressure to said slide block thru said spring and connections.

41. In a machine for condensing piston rings in accordance with a predetermined law, the combination of a condensing roller arranged to contact with the inside of the ring, a sliding pressure applying roller, a slide block in which the pressure applying roller is mounted, a rotary member, a movable head, connections between said head and said rotary member and a heavy spring and a light spring between said head and said slide block, a spring adjusting screw secured to one of said last two members, said screw being surrounded by said springs, the rotation of said rotary member moving said head and applying pressure to said slide block thru said spring and connections.

42. In a machine for condensing piston rings in accordance with a predetermined law, the combination of a ring holder for holding the ring in position, a condensing roller arranged to contact with the inside of the ring, a sliding pressure applying roller, a slide block in which the pressure applying roller is mounted, a rotary member, a movable head, connections including a spring between said head and said slide block, means for adjusting said spring, the rotation of said rotary member moving said head and applying pressure to said slide block thru said spring and connections.

43. In a machine for condensing rings, the combination of a tapered condensing roller arranged to contact with the inside of the ring, means for rotating said ring and one or more springs for producing pressure between said condensing roller and said ring.

44. In a machine for condensing rings, the combination of a tapered condensing roller, arranged to contact with one of the curved faces of the ring, means for rotating said ring and means for producing pressure between said condensing roller and said ring.

45. In a machine for condensing rings, the combination of a tapered condensing roller, arranged to contact with one of the curved faces of the ring, means for causing relative rotation between said ring and the point of contact of said roller with said ring.

46. In a machine for condensing piston rings, the combination of a holder for the ring, means for rotating the holder, a con-

densing roller arranged to contact with the inside of the ring, said roller being free to initially move bodily in the direction of rotation of the ring, a pressure applying roller arranged to apply pressure to the holder, and means for varying the pressure applied to said pressure applying roller, a housing for said roller, said roller provided with axial extensions, and said housing having a notch to receive said roller, said extensions contacting with the upper and lower portions of said housing above and below the notch.

47. In a machine for condensing piston rings, the combination of a holder for the ring, a gear, means for securing said holder to said gear, a drive shaft, said shaft being geared to said gear, a condensing roller arranged to contact with the inside of the ring, a pressure applying roller arranged to apply pressure to the holder and a second gear driven from said drive shaft, a crank pin carried by said second gear, and connections between said crank pin and the pressure applying roller.

48. In a machine for condensing piston rings, the combination of a holder for the ring, a gear, means for securing said holder to the face of said gear, a drive shaft, said shaft being geared to said gear, said drive shaft carrying a worm, said worm driving said gear, a condensing roller arranged to contact with the inside of the ring, a pressure applying roller arranged to apply pressure to the holder and a second gear driven from said drive shaft, a crank pin carried by said second gear and connections between said crank pin and the pressure applying roller.

49. In a machine for condensing piston rings, the combination of a bed plate, a drive shaft extending along said plate, a worm carried by said shaft, a pair of gears engaging with said worm and arranged on opposite sides of said drive shaft, a ring holder secured to the face of one of said gears, a condensing roller arranged to engage the inside of said ring, said ring holder being bodily movable in the direction of the pressure, a crank pin carried by the other of said gears, a connecting rod having one end connected to said crank pin, a link to which the other end of the connecting rod is connected, a pressure applying roller, and a yielding connection between said pressure applying roller and said link.

50. In a machine for condensing piston rings, the combination of a holder for the ring, a shouldered carrier for receiving the holder, means for removably securing the holder to the carrier, means for securing the carrier to the gear, a crank pin carried by the other of said gears, a connecting rod having one end connected to said crank pin, a lever to which the other end of the connecting rod is con-

nected, a pressure applying roller, and a yielding connection between said pressure applying roller and said lever.

51. In a machine for condensing piston rings, the combination of a holder for the ring, a condensing roller arranged to contact with the inside of the ring, a pressure applying roller, means for rotating said holder, a clutch, and means for disconnecting said 10 clutch after said holder has completed one revolution.

52. In a machine for condensing piston rings in accordance with a predetermined law, the combination of a rotary holder for 15 the ring, a condensing roller arranged to contact with the inside of the ring, a sliding pressure applying roller, a slide block in which the pressure applying roller is mounted, a rotary member, a movable head, connections between said head and said rotary member, a spring between said head and said slide block, the rotation of said rotary member moving said head and applying pressure to said slide block thru said spring and connections, a clutch, a pin carried by said head, and 20 connections between said pin and said clutch for disconnecting said clutch after the ring has made one rotation.

53. In a machine for condensing piston 30 rings, the combination of a holder for the ring, means for giving said holder a plurality of revolutions, a condensing roller arranged to contact with the inside of the ring, a pressure applying roller arranged to apply pressure to the holder, means for varying the 35 pressure applied to said pressure applying roller, and means for increasing said pressure for each revolution of the holder, different portions of the completed ring being thus 40 variably condensed.

54. In a machine for condensing piston rings, the combination of a holder for the ring, means for giving said holder a plurality of revolutions, a condensing roller arranged to contact with the inside of the ring, a pressure applying roller for applying pressure to said holder, a crank for varying the 45 pressure applied to said pressure applying roller in accordance with a predetermined law, means for adjusting the throw of said 50 crank, a lever between the crank and the pressure applying roller, said lever engaging a fulcrum, and means for shifting the fulcrum for each revolution of the holder.

55. In a machine for condensing piston 55 rings, the combination of a holder for the ring, means for giving said holder a plurality of revolutions, a condensing roller arranged to contact with the inside of the ring, a pressure applying roller for applying pressure to said holder, a crank for varying the 60 pressure applied to said pressure applying roller, means for adjusting the throw of said crank, a lever between the crank and the pres-

sure applying roller, said lever engaging a 65 fulcrum, means for shifting the fulcrum for each revolution of the holder, said means comprising a shaft, connections between said shaft and fulcrum and means, including a rack and pinion, for rotating said shaft. 70

56. In a machine for condensing piston rings, the combination of a holder for the ring, means for giving said holder a plurality of revolutions, a condensing roller arranged to contact with the inside of the ring, a pressure applying roller for applying pressure to said holder, a crank for varying the pressure applied to said pressure applying roller, means for adjusting the throw of said crank, 75 a lever between the crank and the pressure applying roller, said lever engaging a fulcrum, means for shifting the fulcrum for each revolution of the holder, said means comprising a shaft, connections between said shaft and fulcrum means including a rack 80 and pinion for rotating said shaft, and means for varying the amount of movement of the rack. 85

57. In a machine for condensing piston 90 rings, the combination of a holder for the ring, means for giving said holder a plurality of revolutions, a condensing roller arranged to contact with the inside of the ring, a pressure applying roller for applying pressure to said holder, a crank for varying the 95 pressure applied to said pressure applying roller, means for adjusting the throw of said crank, a lever between the crank and the pressure applying roller, said lever engaging a fulcrum, means for shifting the fulcrum for each revolution of the holder, said means comprising a shaft, connections between said shaft and fulcrum and means for rotating 100 said shaft including a rack and pinion and a pawl and ratchet mechanism, the latter arranged between the rack and pinion and the shaft. 105

58. In a machine for condensing piston rings, the combination of a holder for the ring, means for giving said holder a plurality of revolutions, a condensing roller arranged to contact with the inside of the ring, a pressure applying roller for applying pressure to said holder, a crank for varying the pressure applied to said pressure applying roller, a lever between the crank and the pressure applying roller, said lever engaging a fulcrum, and means for shifting the fulcrum for each revolution of the holder, said 110 means comprising a shaft, a cam carried by said shaft and means for rotating said shaft. 115

59. In a machine for condensing piston rings, the combination of a holder for the ring, means for giving said holder a plurality of revolutions, a condensing roller arranged to contact with the inside of the ring, a pressure applying roller for applying pressure to said holder, a crank for varying the 120 pressure applied to said pressure applying roller, means for adjusting the throw of said crank, a lever between the crank and the pres-

pressure applied to said pressure applying roller, means for adjusting the throw of said crank, a lever between the crank and the pressure applying roller, said lever engaging said fulcrum, and means for shifting the fulcrum for each revolution of the holder, said means comprising a shaft, a cam carried by said shaft, said cam provided with a groove, said fulcrum having a pin engaging said

5 groove and means for rotating said shaft.

60. In a machine for condensing piston rings, the combination of a holder for the ring, means for giving said holder a plurality of revolutions, a condensing roller arranged to contact with the inside of the ring, a pressure applying roller for applying pressure to said holder, a crank for varying the pressure applied to said pressure applying roller, means for adjusting the throw of said

15 crank, a lever between the crank and the pressure applying roller, said lever engaging a fulcrum, and means for shifting the fulcrum for each revolution of the holder, said means comprising a shaft, a cam carried by

20 said shaft, said cam provided with a groove, said fulcrum having a pin engaging said groove, a rack and pinion and pawl and ratchet mechanism for rotating said shaft.

61. In a machine for condensing piston rings, the combination of a holder for the ring, a condensing roller arranged to contact with the inside of the ring, a pressure applying roller for applying pressure to said holder, a crank for varying the pressure applied to said pressure applying roller, and means for marking the ring.

62. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller, said pivoted arm carrying means for marking the ring.

63. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller, said pivoted arm carrying means for marking the ring, said means comprising a flexibly mounted member having a cutting edge to mark the

65 ring.

64. In a machine for condensing piston rings, the combination of a holder for the ring, a condensing roller arranged to contact with the inside of the ring, a pressure applying roller cooperating with said holder, a crank for varying the pressure applied to said pressure applying roller, and means for relieving the pressure on said pressure applying roller.

65. In a machine for condensing piston rings, the combination of a holder for the ring, a condensing roller arranged to contact with the inside of the ring, a pressure applying roller for applying pressure to said holder, a crank for varying the pressure applied to said pressure applying roller, and means for relieving the pressure applied to the holder.

66. In a machine for condensing piston rings, the combination of a holder for the ring, a condensing roller arranged to contact with the inside of the ring, a pressure applying roller arranged to apply pressure to the holder, means for varying the pressure applied to said pressure applying roller, an upper and lower roller contacting respectively with the upper and lower faces of the ring, a pivoted arm carrying the upper roller and means operated by said pivoted arm to relieve the pressure on the holder.

67. In a machine for condensing piston rings, the combination of a holder for the ring, a condensing roller arranged to contact with the inside of the ring, a pressure applying roller arranged to apply pressure to the holder, means for varying the pressure applied to said pressure applying roller so as to variably condense different portions of the completed ring, an upper and lower roller contacting respectively with the upper and lower faces of the ring, a pivoted arm carrying the upper roller, a shaft carrying said pivoted arm, a cam carried by said shaft, and means operated by said cam to relieve the pressure on the holder.

68. In a machine for condensing piston rings, the combination of a holder for the ring, means for giving said holder a plurality of revolutions, a condensing roller arranged to contact with the inside of the ring, a pressure applying roller for applying pressure to said holder, springs for said roller, a crank, for varying the pressure applied to said pressure applying roller, the mechanism being constructed to apply initial, intermediate and terminal pressure to the pressure applying roller, and means for adjusting the throw of said crank.

69. In a machine for condensing piston rings, the combination of a holder for the ring, a condensing roller arranged to contact with the inside of the ring, a pressure applying roller for applying pressure to said holder, a rotatable gear, an adjusting screw carried by said gear, an adjustable crank pin

connected with said screw, an adjustable link connected at one end to said crank pin and connections between said link and said pressure applying roller.

- 5 70. In a machine for condensing piston rings in accordance with a predetermined law, the combination of a holder for the ring, a condensing roller, arranged to contact with the inside of the ring, a pressure applying roller for applying pressure to said holder, a machine bed by which said parts are carried, a base, means for horizontally pivoting said bed to said base, an arm projecting from said bed, and means, for securing said
- 10 roller for applying pressure to said holder, a machine bed by which said parts are carried, a base, means for horizontally pivoting said bed to said base and means for securing said bed at various tilted positions.
- 15 71. In a machine for condensing piston

rings in accordance with a predetermined law, the combination of a holder for the ring, a condensing roller arranged to contact with the inside of the ring, a pressure applying roller for applying pressure to said holder, 20 a machine bed by which said parts are carried, a base, means for horizontally pivoting said bed to said base, an arm projecting from said bed, and means, for securing said arm to said base at various positions where- 25 by the inclination of the bed may be varied.

In testimony whereof, I have signed my name to this specification.

ROBERT BINGHAM WASSON.
